UNITED STATES PATENT OFFICE.

CHARLES H. STOCKING, OF AUDUBON, IOWA.

POULTRY-FEEDER.

1,148,873.

Specification of Letters Patent.

Patented Aug. 3, 1915.

Application filed July 18, 1914. Serial No. 851,771.

To all whom it may concern:

Be it known that I, CHARLES H. STOCKING, a citizen of the United States, residing at Audubon, in the county of Audubon and 5 State of Iowa, have invented a new and useful Poultry-Feeder, of which the following is a specification.

This invention relates to a novel device for receiving and dispensing poultry feed 10 whereby the fowl will be unable to scatter the feed about.

A further object is to provide a poultry feeder which may be dismantled or disassembled and the parts thereof nested together, allowing the same to be economically 15 shipped in bulk.

A further object is to provide a device possessing the aforementioned characteristics and at the same time so designed and 20 constructed as to be light in weight, simple in arrangement, and therefore subject to economical manufacture.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, can be made within the scope of what is claimed, without departing from the spirit of the invention.

In the drawings accompanying this specification and forming a part thereof, the 35 preferred embodiment of my invention is illustrated.

In said drawings:—Figure 1 is a view in side elevation of my novel poultry feeder. Fig. 2 is a sectional view in elevation of the 40 foregoing.

Referring to the drawings in which similar reference numerals designate corresponding parts throughout the several views, a receptacle 3 is provided with the upper curled 45 rim 4 and is preferably of tapering contour so that a number of the receptacles may be nested together to thus occupy a small space, providing for their economical shipment. A plurality of legs 5 are detachably secured to 50 and extend externally of the receptacle 3, being secured thereto by the bolts 6. The bolts 6 extend through suitable apertures 7 and 8 formed in the said legs and receptacle side walls, thus rigidly securing the legs in 55 place and at the same time rendering them conveniently detachable. The legs extend

beneath and contact with the rim 4 which prevents to a large extent any weight being brought to bear upon the bolts.

Three legs have been disclosed in the 60 present drawings as supporting the receptacle, but it will be noted that this number may be varied as consistent with the weight to be supported and the desired stability of the device. A plurality of posts 9 are 65 secured to and contact with the inner surface of the receptacle. The number of posts 9 corresponds to the number of legs 5, in alignment with which they are positioned. The bolts 6 which project through the legs and 70 side walls of the receptacle also project through suitable apertures 10 in the post and thus secure the same in rigid as well as demountable relation. The posts project above the upper rim of the receptacle, and 75 are bent as at 11 to thus define an offset upstanding portion 12 in which are provided the vertical upstanding rows of apertures 13.

A cover 14 is provided with a number of outstanding pins 15 which project within 80 the apertures of the posts and thus adjustably mount the cover thereon. The manner of attaching and detaching the pins consists merely in flexing the arms 12 outward, allowing the pins to aline with the apertures, 85 after which the posts are allowed to reflex, thus effecting the securement in question. The lid is of arcuate section and substantially equal in diameter to the diameter of the receptacle 3. Thus a space S will be defined between the outer edge 16 of the cover and the rim 4 of the receptacle, which space is adjustable, allowing for the insertion of a fowl's head therein, thus rendering the feed within the receptacle accessible but 90 preventing the fowls placing their feet therein, which they seem to possess a natural propensity to do. A screen 17 may be laid upon the feed within the receptacle and thus prevents the feed from being scattered about 95 by the bills of the fowls.

Among the many and desirable features of the foregoing structure, the vertical adjustment of the cover is particularly emphasized as it allows the device to be adjusted according to the size of the fowl. The space S is so adjusted as to accommodate the fowl's head therein without inconvenience thereto, but is made sufficiently small to prevent the fowls from placing their feet 100 therein, thus eliminating the scattering and wasting of the feed. The receptacle is pur-

5 posely made liquid tight so that it may be used in the capacity of a drinking fountain if so desired. The dismountable manner in which the legs and posts are secured to the receptacle allows the device to be packed to occupy but little space and the tapering contour of the receptacle allows a plurality of said receptacles to be nested together for their shipment in bulk.

10 Having thus fully described my invention and enumerated several of its advantages, what I claim is:—

15 1. A poultry feeder comprising a feed receptacle, spaced flexible posts upstanding therefrom, said posts being apertured, a cover interposed between the posts and above the receptacle, and projections on the cover extending into engagement with the posts.

20 2. A poultry feeder comprising a tapering

receptacle, a plurality of legs positioned against the outer wall thereof, a corresponding number of posts positioned internally of the receptacle contiguous to said legs, means extending through said legs, posts, and receptacle side walls detachably securing the same together, said posts including rows of apertures therein, a cover provided with outstanding pins detachably engaging the said post apertures and held in spaced and adjustable relation to the said receptacle and defining a limited entrance therewith.

25 In testimony that I claim the foregoing as my own, I have hereto affixed my signature in the presence of two witnesses.

CHARLES H. STOCKING.
